SELF LOCKING CAP FOR GASOLINE TANKS

Filed Nov. 28, 1930

Fig. 1.

UNITED STATES PATENT OFFICE

EDWIN BRADLEY FAIRCHILD, OF MANILA, PHILIPPINE ISLANDS

SELF-LOCKING CAP FOR GASOLINE TANKS

Application filed November 28, 1930. Serial No. 498,833.

This invention relates to storage receptacles and more particularly to an improved cap for closing the filling neck of a receptacle or tank of the type in which gasoline is stored upon an automobile.

One object of the invention is to provide a cap which, when applied to the filling neck of a gasoline tank, may be firmly secured and prevented from being removed by unauthorized persons.

Another object of the invention is to so construct the cap and the upper end of the filling neck of the tank that, while the cap may be easily applied and moved to a secured position, it cannot be released and removed from the neck without use of a key.

Another object of the invention is to provide the cap with a resilient neck-engaging strip so mounted that, while the cap may be easily applied to the filling neck of the tank, the securing strip will be prevented from having sufficient flexing movement in one direction to permit the cap to be forced upwardly off the neck.

The invention is illustrated in the accompanying drawing, wherein

Figure 1 is a sectional view showing the improved cap applied to the neck of a gasoline tank and secured thereon,

Fig. 2 is a transverse sectional view taken on the line 2—2 of Fig. 1,

Fig. 3 is a fragmentary view showing the neck in vertical section and the cap about to be applied thereto, and

Fig. 4 is a sectional view through a modified form of filling neck.

The tank, which is indicated in general by the numeral 1 represents a tank of a conventional construction such as is used for storing gasoline upon an automobile. This tank may be of any size and dimensions desired and is provided with an upwardly projecting filling neck 2. The neck is open at its ends and at its upper end has its walls bent inwardly and then downwardly to form an annular

flange 3 having a depending circumferentially extending lip 4 about its margins. By this arrangement gasoline may be easily poured into the filling neck when the cap is removed and in addition the flange 3 and its depending lip 4 will also serve to reinforce the upper end of the neck and prevent it from being easily bent out of shape.

In order to close the upper end of the neck 2, there has been provided a cap 5 which may be formed of cast pressed or otherwise shaped metal or a suitable composition. This cap has its lower portion reduced to form a depending extension 6 surrounded by a circumferentially extending groove or recess 7 of sufficient width to receive the upper end of the neck 2 and the extension is recessed from its lower end to form a pocket 8 having its marginal walls formed with opposed openings 9. The depending extension of the cap is of such diameter that, when the cap is applied to the filling neck of the tank, the lip 4 will fit snugly about the extension, and from an inspection of Figures 2 and 3 it will be seen that opposed portions of the flange and lip have been cut to form recesses or passages 10 intended to register with the openings 9 when the cap is first applied to the neck. These passages 10 are cut, as shown in Figures 2 and 3, and each has one side edge cut straight whereas the other side edge has its lower portion curved, as shown at 11, and merging into the lower edge of the lip. A securing strip 12 formed of steel or other resilient metal extends diametrically through the pocket 8 with its ends projecting outwardly through the openings 9, and in order to secure the strip, there has been provided a screw 13 which extends through an opening formed in the strip midway its length and is received in a threaded socket 14 formed in the cap. Therefore, this securing strip will be firmly held in place but may be removed in case replacement thereof is necessary. A lock 15 of a conventional construction and

90

adapted to be actuated by a key 16 is embedded in the cap during molding thereof and this lock has a plunger 17 yieldably held in its projected position in a conventional manner and adapted to be retracted when the key is inserted and turned in the proper direction. An opening 18 to receive the plunger 17 is formed in the flange 3 in spaced relation to one side of one of the passages 10, and from an inspection of Figure 1 it will be readily seen that when the plunger is engaged in the opening it will be impossible to turn the cap upon the neck until the key is inserted and the plunger retracted.

The tank 1 is mounted upon the automobile in the usual manner and the gasoline poured into the tank through the filling neck. After the gasoline has been poured into the tank, the cap is applied in the position shown in Figure 3 and upon being thrust downwardly the ends of the securing strip 12 passed downwardly through the passages 10 until the upper end of the neck is seated in the groove 7. When the cap is first applied and the securing strip passes downwardly through the passage 10, the plunger 17 rests upon the flange at a point about midway between the passage 10 and the opening 18. Therefore, cap may be turned to move the plunger towards the opening 18 without interference. When the cap is turned, side edges of the projecting ends of the securing strip bear against the curved lower end portions 11 of the walls of the passages thereby causing a cam action to take place which forces these ends of the securing strip downwardly until they bear against the lower edge faces of the lip 4. As soon as the plunger reaches the opening 18, it moves downwardly into this opening thereby firmly securing the cap and preventing the cap from being turned in a releasing direction until the key is inserted and the plunger again retracted. It will thus be seen that the cap may not be turned in order to remove it unless a person is in possession of the key. In view of the fact that the securing strip is resilient, it will exert pressure upon the lower edge of the lip and prevent rattling. It should also be noted that since the ends of the strip are passed through openings 9 these end portions of the strip cannot be moved downwardly beyond the position shown in Figure 1. Therefore, an unauthorized person attempting to remove the cap cannot force the cap upwardly out of the neck.

In Figure 4, there has been shown a modified construction. In this form the neck 19 is of an even diameter throughout its height and instead of bending the upper portion of the neck to form a flange having a depending lip, there has been provided a ring 20 which fits snugly into the neck where it is firmly secured by rivets 21. Diametrically opposed portions of the ring are cut to form recesses

or passages 22 corresponding to the passages 10 and in spaced relation to one of these passages the ring is bored to form an opening 23 corresponding to the opening 18. It will be understood that, if so desired, the flange 20 instead of being formed from a ring having opposed portions cut to form the passages 22 could consist of arcuate sections having their ends disposed in spaced relation to each other and cut to form the passages.

Having thus described the invention, I claim:

1. A filling neck open at its upper end, an internal flange in said neck formed with opposed passages opening through its upper and lower edge faces and having a seat disposed in spaced relation to one side of one passage and opening through the upper edge face of the flange, a cap for said neck having a depending portion extending into the neck when applied, a spring strip extending across the depending portion with its ends projecting for passage through the passages of the flange and engagement with the under face thereof when the cap is applied to the neck and turned, means to limit downward movement of the end portions of said strip, and a lock carried by said cap and having a depending plunger to engage in said seat and secure the cap to the neck.

2. A filling neck open at its upper end, an internal annular flange in said neck formed with opposed passages and with a seat spaced from one passage circumferentially of the flange, a side wall of each passage having an arcuate lower portion merging into the lower edge face of the flange, a cap for said neck having a depending portion, the under face of the depending portion being recessed to form a pocket and walls of the pocket being formed with opposed openings, a resilient strip in said pocket having its ends projecting through said openings and adapted to pass through the passages of said flange and engage against the lower edge face thereof when the cap is applied to the neck and turned, a releasable fastener for said spring strip engaged through the same intermediate its length, and a lock carried by said cap and having a depending plunger to engage in said seat and releasably secure the cap against turning when applied to the neck.

3. A filling neck open at its upper end, an internal annular flange in the upper end portion of said neck, a cap for said neck having a body to rest upon the neck and an extension to extend into the neck with the flange fitting snugly about the extension, said extension being formed with a pocket in its under face having walls formed with opposed passages, the flange having opposed recesses formed therein leading from its inner side face and opening through its upper and lower faces, a seat being formed in the flange in spaced relation to one side of one of the passages formed

therein, a resilient securing strip in said pocket having end portions projecting through the passages in the walls thereof and passed downwardly through the passages in the flange and having binding engagement with the lower edge face thereof when the cap is applied to the neck and turned a partial rotation, and a lock carried by the body portion of said cap and having a depending plunger to engage in said seat and releasably secure the cap against rotation when applied to the neck.

In testimony whereof I affix my signature.

E. BRADLEY FAIRCHILD.
